UNITED STATES PATENT OFFICE.

ALBERT H. NELLER, OF FAIRFIELD, IOWA, ASSIGNEE TO THE LOUDEN MACHINERY COMPANY, OF FAIRFIELD, IOWA, A CORPORATION OF IOWA.

SLIDING DOOR.

1,184,983.

Specification of Letters Patent. Patented May 30, 1916.

5. Application filed December 2, 1915. Serial No. 64,708.

To all whom it may concern:

Be it known that I, ALBERT H. NELLER, a citizen of the United States, residing at Fairfield, in the county of Jefferson and 5 State of Iowa, have invented a new and useful Improvement in Sliding Doors, of which the following is a specification.

My invention relates to sliding doors for garages and other buildings where the space 10 for sliding the door is limited, and it consists of one or more sliding doors hinged together and supported by an overhead track having its ends bent at an angle to each other and curved near its center in 15 combination with a supplemental door hinged to the outside edge of one of the other doors, but not connected to or directly supported by the track, whereby it may be opened and closed without disturbing the 20 other doors and doubled back to give the doors connected to the track more room to slide thereon, to occupy less space in the building when opening and closing, and to 25 permit the door to be made the full width of the building. Also of other features set forth in this specification and defined in the claims.

In the accompanying drawings forming a 30 part of this specification Figure 1 is a perspective of the inside of a portion of a building having an opening in one end which is closed by the doors embodying my invention. Fig. 2 is the same, showing the doors partly opened. Fig. 3 is the same, showing the main doors in closed position and the supplemental door opened. Fig. 4 is a plan view showing the main doors partly opened and the supplemental door swung partly 35 back. Fig. 5 is a plan view showing the door closed.

Referring to the drawings, A represents the side walls of a building, such as a 40 garage, and B the gable end of the building below which there is an opening for a door, substantially the entire width of the building.

C and D are two main doors hinged together and provided with several hangers 45 H to slide or run on an overhead track T secured to the building in any suitable manner. The track is bent or curved near its center so its ends are at an angle to each other, and it is secured to one side of the building and to the end above the opening 50 for the door.

E is a supplemental door, or section of the door, hinged to the section C, but having no hanger to run on the track T.

In opening the building the supplemental 55 section E will be opened first by swinging it in on its hinges to admit the attendant and give him the best position for handling the doors. If the space at his disposal is essentially limited he can swing the door E back 60 on its hinges against the door C, or partly 65 so, as shown in Fig. 4. If there is more room he can let it stand, as shown by the dotted lines, or keep it close to the side wall as he runs the doors C and D around the curve 70 in the track from the door opening to the side of the building.

By means of my invention the door opening may be made the full width of the building and yet be completely closed by the 75 door, as shown in Fig. 5. This would be 80 impossible when a curved track is used if the section E had a hanger to run on the track, or was otherwise connected to it. In that case the door opening could only be 85 made as wide as the straight part of the track, or the supplemental section E could not be swung to closed position. This is an important feature, because it permits the door opening to be made the full width of the building instead of having to inclose 90 that part of the end of the building adjoining the curved portion of the track.

In case there should be an obstruction on the side of the building—a box, a bench or an offset on the wall, as indicated by G in Fig. 4—the supplemental section E not having 95 any hangers nor being in any way connected to the track, may be swung back on its hinges against the section C, so that the length of the track required on the side 100 wall A will only have to be long enough to accommodate the sections C and D.

The section E should always be the same height as the sections C and D to close the 105 opening at the side of the other sections, but it should only be wide enough to admit the attendant. The narrower the better if wide enough for this purpose.

To properly support the track at the curve a brace or bar I should be secured to the building as shown in Figs. 4 and 5, to which the track can be attached. Or, in place of the bar I a piece P curved to correspond with the track may be used. When 110 the building is narrow, one main door fitted

with swivel hangers to run around the curve of the track will be sufficient, but in this case the main door should be considerably wider than the supplemental section to properly balance it. Also, the supplemental section should always be hinged to the main door or doors on the side toward which the doors move in opening.

The invention is in every way convenient and economical of space, as well as inexpensive and effective in operation.

What I claim is:

1. In sliding doors having an overhead track curved near its center so its ends will stand at an angle to each other for attachment to an inner end and side of a building, a door provided with hangers to run on the track, and a supplemental section hinged to the main door on the side toward which it moves in opening, said supplemental door being free to be swung back and forth independently of the track.

2. In sliding doors having an overhead track curved near its center so its ends will stand at an angle to each other for attach-

ment to an inner end and side of a building, a door provided with hangers to run on the track, and a supplemental section hinged to the main door on the side toward which it moves in opening, said supplemental door being disconnected from the track and being free to swing back and forth to open and close the door.

3. In sliding doors having an overhead track curved near its center so its ends will stand at an angle to each other for attachment to an inner end and side of a building, a series of doors hinged together and provided with hangers to run on the track, and a supplemental section hinged to one of the main doors on the side toward which the doors move in opening, and being free to be swung back and forth in opening and closing the door.

Fairfield, Iowa, November 30, 1915.

ALBERT H. NELLER.
